UNITED STATES PATENT OFFICE.

JAMES B. BUCHANAN, OF SEATTLE, WASHINGTON.

WAX-CARVER.

1,129,634.

Specification of Letters Patent.

Patented Feb. 23, 1915.

Application filed June 27, 1914. Serial No. 847,676.

To all whom it may concern:

Be it known that I, JAMES B. BUCHANAN, a citizen of the United States, residing at Seattle, in the county of King and State of Washington, have invented certain new and useful Improvements in Wax-Carvers; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to wax carvers, and more particularly to an instrument for use by dentists for hollowing out the wax impression of a cavity; the principal object of the invention being to provide a device, 20 including an aspirator, for melting and siphoning wax from any part of the impression without distorting its shape or marring the surface adjacent the excavation.

It is customary in making dental inlays 25 to make a wax impression of the cavity, secure a casting of the impression in a suitable non-corrosive metal, and cement the casting in the tooth. It has been found that, owing to the weight of the metal and the 30 peculiar shape of some inlays, the limited holding surface is insufficient to prevent the cement from breaking and loosening the filling. In correcting this feature, I have provided an instrument for hollowing out 35 the wax impression or cutting any portion of it away, so that when it is cast it will present the form of a light shell into which a sufficient quantity of cement may be placed to obtain satisfactory anchorage onto the 40 tooth and at the same time cut down the weight of the inlay. In accomplishing these objects, I have provided the improved details of structure hereinafter described, and 45 illustrated in the accompanying drawings, wherein:—

Figure I is an elevation of a wax carver constructed in accordance with my invention. Fig. II is an enlarged longitudinal section of the same. Fig. III is a transverse sectional view on the line III—III, 50 Fig. II. Fig. IV is a similar view on the line IV—IV, Fig. III, looking in the opposite direction.

Referring more in detail to the parts: 1 55 designates a metal body, preferably round and of sufficient size and thickness to retain

heat for a certain period of time. Extending forwardly from said body is a neck 2 having a central aperture 3, which extends into said body and which is adapted to receive a tube 4 having a flared outer end 5. Entering the rear of the body member is a second and smaller aperture 6 in which is rigidly mounted a carving tool 7, comprising a small tube that curves downwardly, as 60 65 shown.

Rigidly mounted on the outer face of the neck 2, and concentric with the tube 4, is a tube 8, which extends a considerable distance beyond the end of the tube 4, and which is provided with a laterally projecting tube 9. The tube 9 is rigidly secured to the tube 8 and enters the same at a point adjacent the neck 2 and at the rear of the flared end 5 of the tube 4 and carries a non-heat conducting tube 11 of fiber or the like, 70 which abuts against a collar 12 on the tube and carries a flexible rubber tube 13 that may be used as a mouth piece or connected 75 directly to a pressure tank (not shown).

In using the device, presuming the parts 80 to be constructed as described, and it is desired to excavate the rear face of the wax impression of a cavity; the instrument is placed over a Bunsen burner and the body 85 1 heated sufficiently to melt wax. The operator then lifts the instrument by grasping the fiber tube 11, touches the carving tool 7 to the wax impression and blows strongly 90 through the rubber tube 13. This action 95 causes air to rush at a high velocity past the tube 4 and creates a suction therein, which is transmitted to the tool 7 and draws the wax, as it is melted, from the impression. It is apparent that as the tube 4 is much larger than the tube 7, the suction 100 through the small tube is much greater, as compared with the velocity of the air through the tube 4, therefore making it possible to secure excellent results with the breath as the motive fluid. By flaring the 105 mouth 5 of the tube 4, the velocity of air from the mouth-piece is increased at this point, and the hot air from the tube 7, which has expanded in the tube 4, is drawn 110 into the current of air, through the tube 8, and thence to the atmosphere. In cleaning the tube 7, which may become obstructed by wax and particles of foreign matter, the body 1 is heated to melt the wax, the finger 110 is placed over the free end of tube 8 and a current of air blown into the tube 13.

Having thus described my invention, what I claim as new therein, and desire to secure by Letters-Patent, is:—

1. A wax carver comprising a heat retaining body, and a carving tool adapted to receive heat from said body.
2. A wax carver comprising a heat retaining body, a carving tool adapted to receive heat from said body, and means for creating suction through said carving tool.
3. A wax carver comprising a heat retaining body, a carving tool adapted to receive heat from said body, and having a central duct, and means for creating suction through said duct.
4. A wax carver comprising a heat retaining body, a carving tool comprising a downwardly turned tube rigidly mounted in and adapted to receive heat from said body, and an aspirator for creating suction through said tool.
5. A wax carver comprising a heat retaining body, a tubular carving tool adapted to receive heat from said body, a tube projecting from the opposite side of said body and communicating with said carving tool, a second tube projecting from said body and concentric with said first tube, and a third tube projecting laterally from and communicating with the second tube.
6. A wax carver comprising a heat retaining body, a carving tool, a tube projecting from the opposite side of said body and communicating with said carving tool, a second tube rigidly secured to said body, and concentric with and projecting beyond said first tube, and a third tube projecting lat-

erally from and communicating with said second tube at a point adjacent said body.

7. A wax carver comprising a heat retaining body, a carving tool comprising a downwardly curved tube rigidly mounted in and adapted to receive heat from said body, a tube projecting from the opposite side of said body, of greater cross section than said carving tool tube, a second tube rigidly mounted on said body and concentric with and projecting beyond said first tube, a third tube extending laterally from and communicating with said second tube at a point adjacent said body, a non-heat conducting tube mounted on said third tube, and a flexible tube on said non-heat conducting tube, for the purpose set forth.

8. In a wax carver, a heat retaining body, a tubular carving tool in said body, a tube having a flared end projecting from the opposite side of said body and communicating with said carving tool, a second tube rigidly mounted on said body, and concentric with and spaced from said second tube to form an annulus therebetween, a third tube communicating with said annulus, and a mouth piece on said tube whereby a current of air may be forced through said annulus and past said flared end to create a suction in said first tube for said carving tool.

In testimony whereof I affix my signature in presence of two witnesses.

JAMES B. BUCHANAN.
